UNITED STATES PATENT OFFICE.

LUCIUS J. PHELPS, OF STONEHAM, MASSACHUSETTS, ASSIGNOR TO
PHELPS MOTOR VEHICLE COMPANY, OF STONEHAM, MASSACHU-
SETTS, A CORPORATION OF MAINE.

MOTOR-VEHICLE.

SPECIFICATION forming part of Letters Patent No. 761,398, dated May 31, 1904.

Application filed April 9, 1903. Serial No. 151,839. (No model.)

To all whom it may concern:

Be it known that I, LUCIUS J. PHELPS, of Stoneham, in the county of Middlesex and State of Massachusetts, have invented certain new and useful Improvements in Motor-Vehicles, of which the following is a specification.

This invention relates to the driving mechanism of automobiles; and it has for its object to mount the motor independently of the vehicle-body without employing an underframe having side reaches or an equivalent construction and to effectively lubricate the driving mechanism of a carriage so constructed.

Of the accompanying drawings, Figure 1 represents a longitudinal sectional view of a motor-vehicle constructed in accordance with my invention. Fig. 2 represents a front elevation of the motor and running-gear with parts in section. Fig. 3 represents a plan view 20 of the rear part of the driving mechanism with part of the casing thereof removed. Fig. 4 represents a detail cross-section showing the oil-duct.

The same reference characters indicate the 25 same parts in all the figures.

Referring to the drawings, 10 indicates the body of the vehicle. 11 11 represent the swinging front or steering wheels, having their axles or knuckles swiveled or hung on a dead front 30 axle or cross-frame 12, and 13 in Fig. 1 is one of the rear or driving wheels, which wheels are secured to independently-rotatable live-axles 14 14, mounted in tubular housings 15 15, forming a part of the running-gear or rear 35 cross-frame of the carriage. The axles 14 enter a compensating-gear box 16, having formed thereon a bevel-gear 27.

18 denotes generically a driving-gear casting or frame member having three principal 40 divisions—namely, a forward division 19, which constitutes the crank-casing of an explosion-motor 22, a middle tubular division 20 of smaller diameter, containing the major part of the length of the driving-shaft, and 45 a rear part 21, containing the clutching and change-speed mechanism.

22 indicates the motor, and 23 indicates the clutching and change-speed mechanism. Said

motor and mechanism and the compensating gear may be of any preferred construction, 50 and being well-known elements of motor-vehicles they are not represented in full detail.

24 is the driving-shaft leading from the motor 22 to the clutching and change-speed mechanism 23, and 25 is a short shaft leading from 55 said clutching and change-speed mechanism and provided with a bevel-pinion 26, meshing with the bevel-gear 27. This train of elements obviously constitutes a rotary driving mechanism whereby the rotation of the motor-shaft is transmitted to the rear-wheel shafts 60 14, so as to propel the carriage, and said mechanism is so inclosed by the casing 18 as to be protected from contact of outside objects and substantially free from entrance of mud, dust, 65 and water. The shaft 24 is shown as provided with a pair of crown-tooth couplings 28, designed to allow for a slight difference in alignment between the two ends of the shaft which is likely to arise in practice from various 70 causes.

The casing 18 is rigid from end to end, and its front end has a yielding support in front of the motor 22 on a transverse leaf-spring 29, whose ends are pivotally suspended by 75 links 30 30 from the ends of the front axle 12 over the body of said axle. This spring is independent of the springs 31 31, whereby the body 10 is yieldingly supported on the front axle 12. The fly-wheel 32 of the motor may, 80 be located, as shown, in front of the spring 29.

The rear part 21 of the casing 18 is made in detachable upper and lower halves 33 34, secured together by bolts 35. In the lower half 34 I form two grooves 36 36 on opposite 85 sides, said grooves following the contour of the casing and having outlets to the bearings 37 37 for the shafts 14, the bearing 38 for the shaft 25, and the bearing 39 for the shaft 24. At their forward ends these ducts open into the 90 rear end of the casing-section 20. At a convenient point in the top of said casing-section is formed an oil-hole 40, whereby oil may be introduced into the interior of the casing, said oil, by reason of the inclination of the casing 18, 95 flowing toward its rear end and entering the

ducts 36, through which it flows to the bearings 39, 38, and 37 and lubricates the latter. In dotted lines in Figs. 1 and 3 there is indicated an oil-duct 41, passing from the rear coupling 28, 5 through which it derives oil from the interior of the casing - section 20, and extending through the middle of the clutching and change-speed mechanism 23, so as to lubricate the latter.

10 It will be understood that the present invention is not limited to the exact construction herein described.

I claim—

15 1. In a motor-vehicle, a longitudinal casing composed of portions joined on a line inclined from the horizontal, power-transmitting shafting having a bearing in said casing, and an oil-duct for the lubrication of said bearing whose walls are formed by the complementary 20 meeting portions of the casing.

20 2. In a motor-vehicle, an inclined longitudinal tubular casing having means at its forward end for the introduction of oil which employs the interior of the casing as a chan-

nel and a motor at its forward end, mechanism 25 traversing said casing for communicating the power of the motor to the driving-wheels and having a bearing at the rear end portion of the casing, and an oil-duct formed in the wall of said casing for conducting the oil from 30 the interior of the casing to said bearing.

3. In a motor-vehicle, a structure consisting of a cross-frame having tubular housings for the independently-rotatable driving-wheel axles and a longitudinal casing, the interior 35 of which forms an oil-channel, a longitudinal driving mechanism traversing and having a bearing in said casing, bearings on said structure for the respective shafts, and oil-ducts carried by said casing for the lubrication of 40 all of said bearings by means of the oil flowing through the interior of the casing.

In testimony whereof I have affixed my signature in presence of two witnesses.

LUCIUS J. PHELPS.
